(57) **CLAIM**

The ornamental design for a floor drain, as shown and described.

DESCRIPTION

FIG. 1 is a front, right and bottom perspective view of the first part of the floor drain, showing my new design; FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of the second part of the floor drain;

FIG. 10 is a rear, left and bottom perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof;

FIG. 17 is a front, right and top a perspective exploded view of the floor drain; and,

FIG. 18 is a front, right and top perspective view of the floor drain shown fully assembled.

The broken lines shown in the drawings illustrate portions of the floor drain that form no part of the claimed design.

The two parts are shown separately for convenience of illustration.
